[57] CLAIM

The ornamental design for a solid fuel heater, as shown
and described.

DESCRIPTION

FIG. 1 is a front perspective view of a solid fuel heater,
showing my new design;

FIG. 2 is a left side perspective view thereof;

FIG. 3 is a right side perspective view thereof;

FIG. 4 is a top plan view thereof;

FIG. 5 is a bottom plan view thereof.

The rear surface of the solid fuel heater is substantially
planar and unornamented.

FIG. I.

FIG. 2.

FIG.3.

FIG. 4.

FIG. 5.
